UNITED STATES PATENT OFFICE.

DOROTHY ZECH, OF LAWRENCEBURG, INDIANA.

GARMENT-TEMPLLET.

1,260,849.

Specification of Letters Patent. Patented Mar. 26, 1918.

Application filed October 17, 1916. Serial No. 126,103.

To all whom it may concern:

Be it known that I, DOROTHY ZECH, residing at Lawrenceburg, in the county of Dearborn and State of Indiana, have invented a new and useful Garment-Templlet, of which the following is a specification.

My invention has reference to improvements in that class of pattern charts or templet-like forms especially designed for 10 use in the making of women's waists and it primarily has for its purpose to provide a device of the character described that is particularly adapted for outlining patterns for plain waists, which is composed of two 15 parts, one constituting a front section and the other a back section, and in which the several adjustable members constituted in each section are so arranged that they may be readily manipulated by any one, whether 20 skilled in the art of dressmaking or not.

With other objects in view that will hereinafter appear, my invention consists, generally, of an improved design of sectional garment templet whose members are relatively adjustable and in such manner that 25 they may be quickly and accurately set to produce the desired size of pattern, and in which the several members of the templet sections, front or back, form extensions for 30 each other, whereby the desired outline or edge may be obtained for designating the pattern on the goods, from which the garment is to be made.

My invention further consists in the design 35 tails of construction hereinafter explained, specifically pointed out in the appended claims and illustrated in the accompanying drawing, in which:

Figure 1 is a plan view of my improved 40 templet or adjustable pattern for the front part of the waist.

Fig. 2 is a plan view of a front pattern cut on the lines of the said templet.

Fig. 3 is a similar view of the templet 45 or pattern section for forming the back part of the waist, and

Fig. 4 is a plan view of a back pattern cut on the lines of the templet shown in Fig. 3.

The templet as shown in Fig. 1 is 50 provided for producing the pattern for the waist front, it being apparent from the drawing that the several parts that constitute the front templet can be relatively adjusted according to requirements.

The front templet comprises two main or 55 central sections, one of which, 1, constitutes

the center front section and the other 2, the under arm front section, the latter having the usual concaved arm socket or curved rear upper edge 20, while the front upper edge 60 of the member 1 has the usual neck curve 10.

The adjacent edges of the two central sections each have a number, preferably a pair, of substantially horizontally disposed slots 3—3, the length of which takes in the maximum limit of extending the two members the full length of the sizes of waists that may be patterned by my templet, and one of the said sections 1—2, preferably that section which is overlapped by the other, has 70 character scales 4 so that the adjustment of one section, relatively to the other, will uncover the different indicating sizes on the scales, as the two sections are adjusted to the required extension limits. 75

In the drawing, I have illustrated the templet section as having relatively such adjustment whereby the templet may be set for delineating a 34" pattern when closed and a 50" pattern when extended to the 80 limit.

22 designates a supplemental section, which I term, the under arm front adjuster and it has an adjusting slot 21 for coöperating with a like slot 23 in the member 2 85 which overlaps it and whose rear edge 24 is utilized for alining the upper and lower character scales 6—6 on the said under arm front adjuster 22.

15 designates what I term the center front 90 adjuster, which coöperates with the front edge of the center front 1 and the said adjuster 15 and the front member 1 have co-acting adjusting slots 16—16 and 11—11, the adjuster 15 being also provided with 95 upper and lower character scales 17—17 located adjacent the slots 16—16.

At a suitable distance from the lower end, the said front member 1 is cut out to produce a horizontal body of a length equal 100 to the extension adjustment of the overlapping members 1 and 2, plus the extra space allowed for seams, which throughout the front and back templet structure need not exceed $\frac{3}{4}$ of an inch. 105

From the inner end of the said bottom edge 8, member 1 is cut to form a dart curve edge 9, the cut of which varies according to the size of the pattern desired and which is determined by the graduating scale 18 110 and for coacting with the said dart curve, the adjacent lower edge of the central sec-

tion 2 is likewise cut to form a dart edge 25, the curvature of which is also determined by the scale 18.

The several adjustable sections are held 5 together and secured to the different adjustments by stud washers and thumb nuts 36 of any approved construction.

The templet form for developing the back part of the waist, embodies the same general 10 characteristics of the front waist developing templet and the said back templet consists of a central or body portion 55 whose upper end terminates with the usual shoulder line 56 and neck curve 57—a central 15 back adjuster 58—a main under arm adjuster 59, and a supplemental under arm adjuster 60.

Adjacent its opposite vertical edges, the central back portion 55 has upper and lower 20 sets of substantially horizontally disposed adjusting slots 62—62 and the center back adjuster 58 has similar slots 63—63 for alining with the slots 62, it also having, adjacent its slots, character scales 64—64, as 25 shown.

The under arm adjuster 59 has slots 65—65 for coacting with the slots 61—61 in the back portion 55 and the inner edge 66 of the adjuster 59 overlaps the upper and 30 lower scales 67—67.

The under arm adjuster 59 also has a supplemental adjusting slot 68, near its lower end, to provide for the required attachment and adjustment of the supplemental under arm adjuster 60, the latter being provided for determining the proper under arm fitting in making the larger sizes of waists, the upper edge 70 of the adjuster being cut on the required curvature to insure 35 the proper under arm pattern lines.

One-third of an inch is deemed sufficient for the dart seams.

From the foregoing description taken in connection with the drawings, it will be 45 readily apparent that while my templet will be found especially useful for dressmakers, the construction thereof is so simple and the manner of its use is so plain that the same may be readily employed by others not specially skilled in the art of dressmaking.

The templet shown, when closed, serves to form a pattern for a 34" bust measure. To adjust it for larger sizes, it is only necessary to take the bust measurement and assuming the same to be 38", it is only necessary to shift the several parts of the front and back templet sections along the several scales to the 38" designating characters to produce the required size of pattern; see for 50 example Figs. 2 and 4.

I am aware that templets or adjustable pattern charts have heretofore been provided for producing patterns for different waist sizes, and in which are included adjustable members, but, so far as I know, they 65

have been more or less complicated and more generally adapted for being used by dressmakers or others skilled in the making of garments.

In my construction, the adjustment of 70 the templet sections, both for the front and back forms, are uniform throughout, *i. e.*, the different members are each adjusted laterally with respect to each other and a careful or special manipulation thereof is 75 not required further than to loosen up the set screws and shift the several sections until the required sizes on the several scales are exposed and then tighten up the set screws.

There are no irregular lines and those that 80 occur fall at the bottom and not at the shoulder or neck lines, which under all adjustments remain true.

After getting the proper pattern adjustments, the templets are placed lengthwise on 85 the material and are then outlined with a tracer or pencil.

What I claim is:

1. A templet for forming the front of a 90 shirt waist, comprising a main center front section having a neck line and a straight shoulder line at the upper end, a supplemental center front section that coöperates with the straight edge of the main center front section, a main under arm section, the 95 inner edge of which is adapted for overlapping the adjacent edge of the main central front section and having an outer edge adapted for being brought into parallelism with the outer edges of the main and the supplemental center front sections, a supplemental straight edge under arm adjuster adapted for coöperating with the outer straight edge of the under arm section, said main and supplemental center front sections 100 and the under arm section and under arm adjuster having adjustment relatively laterally of each other, and means for holding the several sections in their adjusted positions.

2. A templet for forming the front of a 110 shirt waist, comprising a main center front section having a neck line and a straight shoulder line at the upper end, a supplemental center front section that coöperates with the straight edge of the main center front section, a main under arm section, the 115 inner edge of which is adapted for overlapping the adjacent edge of the main central front section and having an outer edge adapted for being brought into parallelism with the outer edges of the main and the supplemental center front sections, a supplemental straight edge under arm adjuster adapted for coöperating with the outer 120 straight edge of the under arm section, said main and supplemental center front sections and the under arm section and under arm adjuster having adjustment relatively laterally of each other, and means for holding 125

130

the several sections in their adjusted positions, the inner edge of the main center front section terminating near its lower end in an inwardly extended right angled shoulder 5 that terminates with a dart curved edge, the coacting edge of the under arm section terminating in a dart curve.

3. A templet for forming the front of a shirt waist comprising a body, the entire 10 outline of which is adapted to constitute a guide for a marker, said body including a vertically extended main center body section and a supplemental center body section for coöperating with the outer edge of the 15 main center body section, the upper and lower ends of the lapped portion of the main and the supplemental center body sections having substantially horizontally located alined elongated slots, connecting elements 20 fitting the slots and corresponding character scales on the said body for effecting the adjustment of the center front sections, an under arm section for coöperating with the inner edge of the main center body section, 25 the meeting portions of the under arm section and the center body portion having substantially horizontally positioned alined slots and corresponding character scales on the body and connecting elements fitting the 30 said slots for effecting the adjustment of the said under arm section, an under arm adjuster that coöperates with the outer edge of the under arm section, the said under arm section and the adjuster having alined horizontally extended slots, a corresponding 35 character scale on the adjuster and connections for engaging the slots to hold the adjuster in its shifted positions.
4. A templet for forming the front of a shirt waist, comprising a body, the entire 40 outline of which is adapted to constitute a guide for a marker, said body including a vertically extended main center body section and a supplemental center body section 45 for coöperating with the outer edge of the main center body section, the upper and lower ends of the lapped portion of the main and the supplemental center body sections having substantially horizontally located alined elongated slots, connecting elements 50 fitting the slots and corresponding character scales on the said body for effecting the adjustment of the center front sections, an under arm section for coöperating 55 with the inner edge of the main center body

section, the meeting portions of the under arm section and the center body portion having substantially horizontally positioned alined slots and corresponding character scales on the body and connecting elements 60 fitting the said slots for effecting the adjustment of the said under arm section, an under arm adjuster that coöperates with the outer edge of the under arm section, the said under arm section and the adjuster having alined 65 horizontally extended slots, a corresponding character scale on the adjuster and connections for engaging the slots to hold the adjuster in its shifted positions, the lower portion of the inner edge of the center body section 70 terminating in an inwardly extended horizontal shoulder that merges with a curved dart edge, the opposing edge of the under arm section having a similar dart edge and a character scale on the center body section located at the beginning of the 75 dart curved edge thereof.

5. A templet for forming the back of a shirt-waist comprising a center back section, a supplemental back section that coöperates 80 with one edge of the center back section, a main under-arm back section adapted to lap the other edge of the center back section, a supplemental under-arm back section for coöperating with the outer edge of the main 85 under-arm back section, and means connecting the several sections whereby they may be readily extended or drawn in relatively to each other and for securing them to their 90 adjusted positions.

6. A templet for forming the back of a shirt waist, comprising a center back section having straight inner and outer edges, a supplemental back section that coöperates with one edge of the center back section and laps 95 over the entire length of the said edge, a main under arm back section adapted to lap the full length of the other edge of the center back section, a supplemental under arm back section for coöperating with the 100 outer edge of the main under arm back section, and means at the upper and lower ends of the said supplemental back section and the main under arm back section and the opposite edges of the main back section 105 whereby the supplemental back section and the main under arm back section may be extended or drawn in in parallelism with their respective edges of the main back section.

DOROTHY ZECH.
